MATTRESS HANDLE

Annette Fridolph, New York, N. Y.

Application February 8, 1940, Serial No. 317,797
In Great Britain February 8, 1939

12 Claims. (Cl. 16—125)

1

The present invention relates to an improved handle for mattresses, upholstery cushions or the like, upholstered articles which are normally awkward to lift or displace.

Usually handles have been provided on the side edges of a mattress which have been stitched to the mattress, but apart from the expense of applying these handles which either has to be done by hand or after the mattress has been manufactured, or by machine stitching prior to manufacture, the disadvantage is present that these handles are apt to become unstitched or torn.

The object of the present invention is to provide a handle which can be rapidly applied to the mattress and which does not involve a special stitching operation.

A further advantage of the present invention is that it will always lie flat against the mattress side and this mattress side is not rucked when the handle is lifted.

According to the present invention a handle of flexible material, usually woven tape, is adapted to be threaded through eyelets formed in the mattress, the ends of this tape having rigid fastenings disposed at or adjacent its ends, co-operating with a rigid bar disposed on the inside surface of the mattress side.

In the drawings:

Fig. 1 illustrates a mattress edge showing the manner in which the handle is attached.

Fig. 2 is a detail elevation of a preferred form of mattress handle.

Fig. 3 is a section taken on the line 3—3 of Fig. 2.

Fig. 4 is a sectional view of a modified form of a handle.

Fig. 5 illustrates the use of the handle device on a single fabric sheet.

Fig. 6 is a detail section, illustrating the manner in which the stiffened end of the handle is formed.

Fig. 7 is a plan view of a modified form of a handle.

Fig. 8 is a sectional view taken on the lines 8—8 of Fig. 7 showing the manner in which the stiffened back and eyelet are used in combination with the outer surface of the mattress.

Fig. 9 is a sectional view of a form of handle in combination with a ventilating device.

Fig. 10 is an elevation on the lines 10—10 of Fig. 9.

Fig. 11 illustrates a modified type of screen for use with the device.

Fig. 12 is a sectional view of a further modified type of screen of a ventilator.

Fig. 12a is a view on the lines 12a—12a of Fig. 12.

Fig. 13 is an elevation of a button type of holder in combination with the stiffened back.

2

Fig. 14 is a sectional view on the lines 14—14 of Fig. 13.

Figs. 15 and 16 illustrate two sides of a combination ventilator and handle holder with a novel type of stiffening back.

Fig. 17 is a sectional view on the lines 17—17 of Fig. 15. Lines 16—16 of Fig. 17 show the direction of the elevation of Fig. 16.

In one preferred form of construction, a thin steel or other metal strip 25 of rigid material is provided with eyelets or openings 26 which are spaced apart at a substantially less distance than the space between similar openings 27 in the mattress side M. The openings in the mattress side M may be provided with eyelets 28. A flexible handle 29 is then provided which has at each end relatively stiff transverse heads 30 formed thereon which preferably have a width slightly greater than that of the handle. The handle is preferably formed of fabric and the relatively stiff ends are formed, for example, by folding the fabric end of the tape forming the mattress handle around a clip 31 of U-shaped section and then collapsing the clip so that the fabric becomes embedded therein and also surrounds it (see Fig. 6). This clip 31 may either be the full width of the tape or wider. The aperture 26, however, must necessarily have a transverse width less than the length of the clip. The end 30 of the handle 29 is arranged to pass longitudinally through the holes 26 and then straightened around transversely of the hole so that it will be retained on the back side of the plate 25. This plate 25 which is of rigid, relatively stiff material, as compared to the handle 29, is itself flexible and resilient, and while it acts as a reinforcing bar, it also normally holds the handle taut and permits flexing of the mattress wall when the hand engages the handle.

The reason for spacing the holes 26 at a less distance than the holes 27, is to obtain a better balance when the mattress side M is held tight, as it would be in the case of a complete mattress. M may also represent the side of an upholstered seat or of a suitcase, or any other similar type of article. This spacing divides the strain and does not allow all of it to be on the heads 30 or on the eyelets 28. A construction similar to Fig. 3, except that the side of the article is a single strip 35 of fabric, is shown in Fig. 5 where the handle 29 passes through a grommet or eyelet 32 in a fabric wall 33.

The openings 26 in the metal strip or back plate 25 may be in the form of punched openings 55 or may be formed, as shown in Fig. 4, by making U-shaped slits and then bending in a tongue or tab 34. As shown in the drawing, a back plate 35 has openings 36 spaced apart at a distance substantially equal to the distance between 60 grommets 28 in the wall M. The ends 30 of the

handle 29 are passed through the grommets 28, holes 36 and then threaded through openings 37 formed by the struck out portion 34. When released, the heads 30 assume a transverse position and one edge bears on the ends of the tabs 34, thus providing an abutment surface for the heads. This construction has an added feature in that the tab 34 forms a smooth joint or corner with the back plate 35 and, therefore, presents cutting of the tape.

In Figs. 7 and 8, the openings in the mattress side M and the back plate 40 register so that an eyelet 41 at each of the registered openings may form a grommet around the openings and clamp the two parts together. Handle 42 provided with heads 43 then passes directly through the grommet and is retained thereby.

In Figs. 9 and 10 is illustrated a construction which combines the features of the constructions shown in Figs. 4 and 8. In this construction, common grommets 41 are used for the back plate 35 and mattress wall M and the struck out portions 34 are used to retain the head 30 of handle 29. An additional feature of this construction is the ventilating and screening combination which consists of small pieces of screen 44 which are placed over the openings in grommets 41 and held in place by an adhesive tape strip 45 extending the length of and adhered to the plate 35 except at the screens where the tape 45 is apertured.

A modified construction for the screening arrangement is illustrated in Fig. 11 where a square screen portion 46 is provided with end tabs 47 and 48. A transverse slot 49 is formed near the end of a back plate 50 to receive the tab 48 and the tab 47 passes through hole 37 already formed in the plate which also receives the head of the mattress handle. Another manner of fastening this screen is shown in Figs. 12 and 12a where a screen portion 51 is provided with a transverse slot 52 through which passes a tab member 53 forming the handle.

Figs. 13 and 14 illustrate the use of a relatively stiff back plate 55 with a handle 56 held to mattress wall M by studs 57 formed on back plate 55 and a snap button 58 which cooperates with the studs. The base of the button 58 is provided with an opening surrounded by radial slots which permit temporary deforming of the base until the ends of the studs 57 are locked in place. In Figs. 15, 16 and 17 is illustrated a novel type of back plate 60 which is designed to permit easy attachment for quick assembly. The back plate 60 is considerably shorter than the distance between grommets 61 which are shown mounted in mesh ventilators 62. Adjacent each end of the back plate 60 is a transverse slot 63, each of which is connected to the respective ends of the plate by longitudinal slots 64. In assembly, it is simply necessary to draw the ends of the tab 29 through the slot 64 and position the head 30 transversely of slot 63. The margins of slot 63 will then serve to hold the head in place and the parts in assembly.

I claim:

1. A handle for use on upholstered articles such as mattresses or the like comprising a fibrous wall having spaced apertures formed therein, a flexible handle strip, means at each end of said handle forming a transverse, relatively stiff head, and means freely positioned behind said wall for receiving said heads comprising a relatively stiff member extending along said wall in alignment

with the apertures therein, said heads being arranged to be projected through said apertures and retained by said member by margins of apertures of less width than said heads, said handle being arranged to extend between said apertures on said wall.

2. A handle for a mattress or a like article comprising a flexible strip having its respective ends passing through spaced apertures in a wall of said article, a relatively stiff, transverse head on each end of said strip, and a relatively stiff back plate positioned freely behind said wall provided with apertures to receive and retain said heads.

3. A handle for a mattress or a like article comprising a flexible strip having its respective ends passing through spaced apertures in a wall of said article, a relatively stiff, transverse head on each end of said strip, and a relatively stiff back plate behind said wall independent thereof provided with apertures to receive and retain said heads, said back plate apertures being spaced a substantially less distance apart than said wall apertures.

4. A handle for a mattress or a like article comprising a flexible strip having its respective ends passing through spaced apertures in a wall of said article, a relatively stiff, transverse head on each end of said strip, and a relatively stiff back plate loosely positioned behind said wall provided with apertures to receive and retain said heads, said back plate apertures being spaced a substantially less distance apart than said wall apertures.

5. A handle for a mattress or a like article comprising a flexible strip having its respective ends passing through spaced apertures in a wall of said article, a relatively stiff, transverse head on each end of said strip, and a relatively stiff back plate loosely positioned behind said wall provided with apertures to receive and retain said heads.

6. A handle for a mattress or like article comprising a flexible strip having its respective ends passing through spaced apertures in a wall of said article, a relatively stiff, transverse head on each end of said strip, and a relatively stiff back plate behind said wall provided with a first pair of apertures spaced substantially as the apertures in the wall of said article and arranged to have the ends of said flexible strip passing therethrough, and a second pair of apertures in said plate spaced within said first pair and arranged to receive and retain said heads by reason of the contact between the margins of said second pair of apertures and the ends of said heads.

7. A handle for a mattress or like article comprising a flexible strip having its respective ends passing through apertures spaced in a wall of said article, a relatively stiff, transverse head on each end of said strip, and a relatively stiff back plate behind said wall provided with a first pair of apertures spaced substantially as the apertures in the wall of said article and arranged to have the ends of said flexible strip passing therethrough, and a second pair of apertures in said plate spaced within said first pair and arranged to receive and retain said heads by reason of the contact between the margins of said second pair of apertures and the ends of said heads, said second pair of apertures being formed by striking tabs from said plate which tabs are disposed at an angle thereto, pointing toward the inner side of the wall of said article and toward each other.

8. A handle for a mattress or like article com-

prising a flexible strip having its respective ends passing through spaced apertures in a wall of said article, a relatively stiff, transverse head on each end of said strip, a relatively stiff back plate behind said wall provided with a first pair of apertures spaced substantially as the apertures in the wall of said article and arranged to have the ends of said flexible strip passing therethrough, and a second pair of apertures in said plate spaced within said first pair and arranged to receive and retain said heads by reason of the contact between the margins of said second pair of apertures and the ends of said heads, said second pair of apertures being formed by striking tabs from said plate which tabs are disposed at an angle thereto pointing toward the inner side of the wall of said article and toward each other, the ends of said tabs being adapted to cooperate to hold the heads of said strip in place.

9. A handle for a mattress or like article comprising a flexible strip having its respective ends passing through spaced apertures in a wall of said article, relatively stiff, transverse heads on the ends of said strip adapted to lie transversely of the ends of said strip, and a locking means freely positioned behind the wall of said article comprising a relatively stiff plate having openings therein at each end, each adapted to receive a head of said flexible strip and to retain the same by contact of the head with the margins of the opening.

10. A handle for mattresses or like articles including a reinforcing bar concealed within the article, apertures formed in said bar, a flexible handle member, relatively stiff ends on said handle member extending into the mattress at points a substantial distance apart to engage said reinforcing bar by passing through and extending transversely of said apertures, said bar being free of the mattress wall and permitting flexing of the

mattress wall when the hand engages the handle.

11. A handle for use on fibrous walls of upholstered articles or the like comprising a pair of grommets extending through said wall in spaced relation, a resilient reinforcing bar to overlie loosely the inner surface of the wall, a flexible cord or tape overlying the outer surface of the wall and passing through said grommets and means on said flexible handle and means on said bar whereby the two are joined to furnish mutual support on the fibrous wall.

15 12. A handle for use on fibrous walls of upholstered articles and the like comprising a pair of grommets extending through said wall, a flexible handle cord or tape overlying the outer surface of the walls and passing through the grommets, means at each end of said handle cord or tape forming a transverse relatively stiff head and an apertured, resilient, reinforcing bar to overlie loosely the inner surface of the wall, said heads being arranged to be passed through said apertured bar and retained by marginal contact therewith whereby said flexible handle and bar mutually support each other in a floating position on said wall.
